CONSTRUCTION AND MOUNTING OF FUEL
BURNER NOZZLES, ESPECIALLY FOR GAS
TURBINES AND LIKE APPARATUSGeoffrey Bertram Robert Feilden, Lutterworth,
England, assignor to Power Jets (Research &
Development) Limited, London, EnglandApplication January 14, 1946, Serial No. 641,145
In Great Britain January 16, 1945

9 Claims. (Cl. 60—39.31)

1

This invention relates to combustion apparatus more especially of a combustion gas turbine, in which fuel is burnt in a flame tube enclosed within an air duct carrying a flow of combustion-supporting air past the flame tube from a point upstream to a point downstream thereof, the fuel being injected into the flame tube by a burner mounted for downstream injection relative to said flow. The invention is concerned particularly with the construction and arrangement of fuel burner nozzles, sometimes called injectors, in such apparatus. It has particular reference to, but is not limited in application to, gas turbines for aircraft propulsion and in relation to that art the invention is especially applicable to engines in what is known as the "straight-through" category, that is to say, in which the combustion system is disposed between a compressor and a turbine in such a way that the general sense of direction of gas flow therethrough is more or less straight, being axial and rearward. In a particular example of the invention later to be described, the engine is one having a multistage axial flow compressor with an annular diffuser outlet leading into an annular combustion chamber containing a plurality of axially directed flame tubes or other combustion elements, the outlet of the combustion chamber being united direct to the nozzle ring of the turbine, the whole comprising a gas turbine aero engine which in general form is symmetrical about its own main axis. This is mentioned, because it is to such a case that the invention has at present direct application, though it will be seen from the following broader statement that it is not limited thereto. The upstream end of the flame tube has a focal point of attachment at or in the region of the burner nozzle. In the art it is common to describe a liquid fuel injection nozzle simply as a "burner" and this word will be used in the following description and claims. A class of burner to which the invention particularly relates is that in which a vortex chamber is employed in which the fuel is caused to swirl and to be ejected through a small orifice from which it sprays with fine atomization. The invention is concerned with the construction of burner, its removability, its mounting and its associated ducting and it is an object of the invention to provide a construction in which a burner, being itself reasonably simple, compact and easily made, can be removed and replaced with a minimum of preliminary movement away from its support and which when mounted is supported robustly so that it can if necessary be used for the further support of a flame tube or its equivalent, whilst the

2

necessity is avoided for specially provided unions with its fuel supply ducting extraneous to its mounting. A burner according to the invention is therefore capable of being mounted direct on part of the engine structure in an internal and normally inaccessible location. The internal mounting of a burner in a gas turbine engine presents many difficulties which the invention seeks to overcome, but at the same time such internal mounting has in some designs of engine great inherent advantage.

According to the invention, in a combustion apparatus of the kind indicated, the burner body is detachably mounted for downstream injection on a structural member which extends across the ducting carrying the gas stream and divides such stream, the fuel supply connection to the burner passing through the said structural member and the burner body forming a point of support for the upstream end of the flame tube into which the fuel is injected, said support being such as to allow axial withdrawal of said flame tube from the burner mounting, and including releasable locking means adapted to retain said flame tube against involuntary displacement. It is intended that the burner should be releasably coupled to the fuel supply connection by means which allow the removal of such body independently of its fuel supply connection. Thus, in this last connection, a preferred embodiment of the invention is one in which appropriate fuel ducting opens at a face or platform on the structural member, and the burner body is applied to said face, the fuel ducting in the burner body registering with that of the structural member, and the construction being such that sealed fluid-flow engagement of the respective ducts is effected by the act of mounting the body on the structural member, without involving pipe unions.

In accordance with a further particular form of the invention, the structural element upon which the burner is mounted is a partition dividing radially an annular duct, for example, the annular outlet duct of an axial flow compressor, there being a number of such partitions spaced around the axis of the compressor to define axial diffuser passages and each carrying a burner.

Further features of the invention will become apparent from the following description with reference to the accompanying drawings, which illustrate by way of example two constructional embodiments of the invention, and in which:

Figure 1 is a part sectional elevation of the forward part of a jet propulsion gas turbine power

unit of a design to which the invention has particular application;

Figure 2 is a fragmentary axial section through the outlet annulus of a compressor such as that illustrated in Figure 1, showing the mounting of a fuel burner and a part of an associated combustion casing or flame tube;

Figures 3 and 4 are sections respectively on lines 3—3 and 4—4 of Figure 2;

Figure 5 is a view similar to Figure 2, but illustrates a different type of burner and mounting.

In the power unit illustrated in Figure 1 the principal elements are an axial flow compressor generally indicated as 1 supplying air by way of an outlet annulus generally indicated at 2 to an annular combustion arrangement generally indicated as 3, from which the products of combustion and air pass to an axial flow turbine generally indicated as 6. The compressor, which is conventionally illustrated since its precise details of construction are not relevant to an understanding of the present invention, comprises a bladed rotor 1a and a bladed stator 1b, of which the former is connected by a shaft 1c with a rotor 6a of the turbine 6 to be driven thereby. In place of the usual stationary guide blading, the axial flow turbine 6 has rotary nozzle blading 6b carried by a rotor 6c disposed upstream of the rotor 6a and supported through bearing means 6d on a stationary bearing sleeve 6e within which the shaft 1c has its rear bearing. The nozzle blading 6b carries, radially outwardly, a rotary shroud 6f supporting the interstage guide blading of the turbine. The turbine exhausts by a duct 6g terminating in a propulsive jet (not shown) which is surrounded concentrically by an augmentor duct 6h in which runs thrust augmenting blading 6i carried by the nozzle blading 6b.

The combustion arrangement 3 comprises inner and outer walls 3a, 3b together forming an annular air casing connecting the compressor outlet 2 and the turbine 6. In the annular air casing are arranged individual flame tubes 4 in which combustion actually takes place, a part of the total airflow being admitted for that purpose through suitable ports in the flame tubes, and the remainder of the air passing around the outside of the flame tubes to mix with the products of combustion at the outlets therefrom. Each flame tube 4 is supported at its downstream end so as to be capable of some rearward axial movement by telescoping with a fixed outlet chute 4a supported as a part of the main structure by means of a hollow strut 4b, and at its upstream end on a fuel injection nozzle or burner 5, the last mentioned support being shown conventionally in Figure 1 and in greater detail in alternative constructional forms in Figures 2-5.

In accordance with the invention, the fuel burners 5 are mounted each at the downstream edge of a radial partition or splitter 7 extending axially in the compressor outlet annulus 2 (that is to say, in the same general direction as the air stream), there being several of such partitions defining axial outlet channels and each mounting a burner.

Each splitter is of substantially aerofoil form in axial cross section and has a radial passage 8 which not only accommodates a pipe connection 10 for the external supply, but also constitutes a passage for the flow of cooling air between the outer atmosphere and the inner chamber enclosed by the compressor outlet annulus 2. One or more further passages 11 are drilled between the radial passage 8 and the downstream

edge of the splitter to provide for fuel connections to the burner.

In the construction illustrated in Figures 2 to 4 there are two such axial passages 11 each with a liner 12 of such a length as to project from the splitter body at each end of its passage. At their upstream ends the liners 12 make spigot and socket engagement with corresponding supply and discharge bores 13 in the pipe connection 10, a fluid-tight seal being obtained by suitable packings as at 14. At their downstream ends the liners 12 make similar engagement with supply and return bores 15 in the burner body 5, sealing rings 16 being again provided. The pipe connection 10 is held rigidly to the splitter by bolts 17 passing through the splitter to engage the pipe connection 10. These bolts have squared heads 17a tapped to receive further bolts 17b by which the burner body 5 is secured against the splitter 7.

The ducting system of the burner is of the kind in which there are tangential swirl ports 18 connected to a swirl chamber 19 having a discharge nozzle 20 and spill duct 21 for the return of sur- plus fuel to the supply. The nozzle 20 is formed in a separate end plate held in position by a sleeve nut 22 having air passages 23 therethrough and provided with a part-spherical outer rim mating with a corresponding seating of a screwed sleeve 24 to which the upstream end of a flame tube 4 is attached, the spherical seating of said sleeve 24 being held in engagement with that of the burner by a threaded locking sleeve 25 which is dimensioned and shaped to form an air passage at 26 between itself and the burner body and communicating with the passages 23, so as to supply air within the flame tube 4 in the vicinity of the discharge nozzle 20. The sleeve 25 is secured by a wire fastener 25a.

40 The trailing edge of the splitter is bossed at 27 to provide a plane face for the attachment of the burner body. Whilst, however, the main body of the burner is cylindrical, its supporting base is of flattened cross section and the fuel ducts and bolt holes formed in a line along it corresponding to the trailing edge of the splitter, so that a minimum of aerodynamic interference may be achieved.

45 In the alternative construction illustrated in Figure 5, a single duct burner is used. In this case the burner support comprises a ferrule 30 which is locked in an axial duct 11 in the splitter by threaded engagement at one end with the pipe connection 10 and at the other with a lock nut 31. The burner body and the ferrule have complementary part spherical seatings which are held in engagement by a union nut 32, whilst the flame tube mounting sleeve 24 is in this case threaded externally for engagement by a securing nut 34 which holds the sleeve 24 against a seating flange 33 on the burner body. The sleeve 24 also provides the air passage 26 to the region of the burner nozzle.

50 Whilst the invention has been described in its adaptation to a particular form of engine such description is not limitative; a further direct application of the features of the invention is one in which burners are required to be mounted internally in a high velocity duct of air, for example for reheating purposes, forming part of or ancillary to a gas turbine propulsion installation.

I claim:

55 1. A combustion apparatus comprising a duct carrying a combustion-supporting air flow, a structural member attached at its ends to op-

posed walls of the duct and extending across the duct to divide the air flow, through which member passes a fuel supply passage, a flame tube enclosed by and extending longitudinally of said duct and located downstream of said member, a fuel injection burner receiving fuel from said supply passage detachably mounted on the downstream side of said member and having a body extending downstream therefrom, a socket at the upstream end of the flame tube forming with the burner body a spigot connection engageable and disengageable in direction of flow, and retaining means to restrain said flame tube against involuntary displacement.

2. A combustion apparatus as claimed in claim 1, having means securing said burner body directly to said structural member, said fuel supply passage and body having registering ports which are brought into sealed fluid-flow engagement when said body is secured on said structural member.

3. A combustion apparatus as claimed in claim 1, having means securing said burner body directly to the said structural member, said burner body having a base mounting provided with a port, said port registering with a complementary port formation of the supply passage and cooperating with said formation to form a spigot and socket joint, and said ports being brought into sealed fluid-flow engagement when said body is secured on said structural member.

4. A combustion apparatus as claimed in claim 1, having a supply connection projecting from said structural member, said burner body being directly and releasably connected thereto.

5. A combustion apparatus comprising an annular duct carrying a combustion-supporting air flow, a plurality of partitions attached at their ends to the inner and outer walls respectively of the duct and extending radially across the duct to divide it into segments, through each of which partitions passes a fuel supply passage, a like number of flame tubes annularly disposed within and extending longitudinally of said duct, each being located downstream of one of said partitions, a like number of fuel injection burners, each receiving fuel from one of said supply passages and being detachably mounted on the downstream side of a partition and having a body extending downstream therefrom, a socket at the upstream end of each flame tube forming with the burner body a spigot connection engageable and disengageable in the direction of flow, and retaining means to restrain the flame tubes against involuntary displacement.

6. A combustion apparatus comprising an axial flow compressor having an annular axially directed outlet, an annular duct receiving a combustion supporting air flow from said compressor outlet, a plurality of partitions attached at their ends to the inner and outer walls respectively of the outlet, and extending radially across the outlet to divide it into segments, through each of which partitions passes a fuel supply passage, a like number of flame tubes annularly disposed within and extending longitudinally of said duct, each flame tube being located downstream of one of said partitions a like number of fuel injection burners, each receiving fuel from one of said supply passages and being detachably

mounted on the downstream side of a partition and having a body extending downstream therefrom, a socket at the upstream end of each flame tube forming with the burner body a spigot connection engageable and disengageable in the direction of flow, and retaining means to restrain the flame tubes against involuntary displacement.

7. A gas turbine plant comprising an axial flow compressor having an annular axially directed outlet, an annular duct receiving the output from said compressor outlet, a turbine nozzle annulus receiving the output from said duct and an axial flow turbine, said compressor, duct, nozzle annulus and turbine being coaxially arranged for substantially straight through flow, a plurality of partitions attached at their ends to the inner and outer walls respectively of the outlet, and extending radially across the outlet to divide it into segments, a like number of flame tubes annularly disposed within and extending longitudinally of said duct, each flame tube being located downstream of one of said partitions, a like number of fuel injection burners, each being detachably mounted on the downstream side of a partition and having a body extending downstream therefrom, a socket at the upstream end of each flame tube forming with the burner body a spigot connection engageable and disengageable in the direction of flow, and retaining means to restrain the flame tubes against involuntary displacement.

8. A gas turbine plant as claimed in claim 7, wherein each partition element supporting a burner has a radially extending passage therein and an axially directed aperture in its downstream wall which communicates with said radial passage, and wherein standing fuel supply ducting is accommodated in the passageways thus formed, and the burner is mounted on said downstream wall, said burner having fuel receiving ducting mating with said fuel connections to receive fuel therefrom.

9. A gas turbine plant as claimed in claim 8, wherein said fuel supply ducting includes a tube extending through the passage formed in said downstream wall and projecting therefrom at each end, said projections forming with complementary formations of the burner body and a fuel supply pipe connection in said radial passage a spigot and socket joint.
